UNITED STATES PATENT OFFICE.

ARTHUR JAMES CUMNOCK, OF RYE, NEW YORK.

MACHINE FOR TREATING PLIABLE TUBES.

No. 829,698.

Specification of Letters Patent.

Patented Aug. 21, 1906.

Application filed April 19, 1905. Serial No. 256,384.

To all whom it may concern:

Be it known that I, ARTHUR JAMES CUMNOCK, a citizen of the United States, and a resident of Rye, New York, have invented 5 certain new and useful Improvements in Machines for Treating Pliable Tubes, of which the following is a specification.

My invention relates to a machine for treating fabrics, which may be in the form of tubular webs either woven or knitted.

In a broad aspect it comprises means adapted to be placed within the tubular web for supporting and, if desired, for stretching the same, together with means for moving 15 the web over such supporting means.

It may also include any desired means for treating the web during its passage over the supporting means—that is, the supporting means may be used merely for stretching and 20 shaping the web, or the web may during its passage be inspected, sheared, singed, or otherwise treated.

A further development of my invention comprises the separating and supporting of 25 the web as above described and while or after it is so separated and supported cutting or piercing it, and particularly cutting it into pieces of desired form for any particular purpose.

For the purpose of illustrating the invention I have shown and will describe a machine for shearing and trimming webs to produce therefrom garment-bodies or other articles. The tubular web may be woven, as 30 shown in my pending application, Serial No. 205,695, filed April 30, 1904, or in any other desired manner. I have shown my machine as arranged to cut from a tubular web shirt-bodies, though it may obviously be so modified as to cut articles of other shapes and for 35 other purposes, as desired.

In the drawings, Figures 1 and 2 are respectively front and side elevations of my device. Fig. 3 is a vertical section through the line 3 3 of Fig. 2. Figs. 4 and 5 are elevations of 45 aprons detached from the rolls on which they are carried. Fig. 6 is a transverse section on the plane 6 6 of Fig. 3. Fig. 7 is a vertical section through the plane 7 7 of Fig. 3. Fig. 8 is an elevation of a portion of a sprocket-chain detached. Fig. 9 is an end view of the 50 rolls shown at the lower portion of Fig. 3 detached from the frame. Fig. 10, on a reduced scale, shows the pieces cut from the web. Fig. 11 designates a supporting-frame having a 55 bed-plate or bed 11 and uprights 12, on which

are mounted standards 13 and 14, the standard 13 being stationary and the standard 14 being adapted to slide toward and from the standard 13 in keyways at its upper and 60 lower ends by means of a screw 141. (See Figs. 1 and 3.) The standard 13 consists, as shown in Fig. 6, of two upright bars 15 and 16, having inwardly-projecting ribs 17 and spaced apart by a block 18, leaving a recess 19. Between the uprights 15 and 16 are mounted 65 sprocket-wheels 2, the shafts 21 of which are connected by suitable speed-gears (see Fig. 2) to a main driving-shaft 22. Sprocket-idlers 23 are also mounted between the uprights 15 and 16, and over these and the sprocket-wheels 2 run sprocket-chains 24, the links 25 of which have lateral projections 26, formed with lateral recesses 27 and a front recess 28, from the inclined faces 29 of 70 which project teeth 210. (See Figs. 8 and 9.) It will be noted that it is the sprocket-wheel 2 at the left of the drawings, Figs. 1 and 3, that is positively connected with the main driving-shaft 22 and that the opposite sprocket-wheel (shown at the right of those figures) is connected to rotate simultaneously therewith by means of a cross-shaft 211. On this cross-shaft is splined a collar 212, (shown in dotted lines, Fig. 1,) carrying a bevel-pinion 85 213, engaging with a similar pinion 214 on the shaft 21. The collar 212 rotates freely in a bracket 215 on the upright 14, so as to move therewith.

Mounted in suitable bearings in cross-bars 90 110, extending between the frame-uprights 12, are trunnions 3 and 31, four in all, to each of which is secured a drum-supporting disk 32. On the trunnions 3 are gear-wheels 33, meshing with oppositely-pitched worms 34, 95 which are connected by suitable trains of speed-gears (see Figs. 1 and 2) with the main shaft 22. Between each pair of disks 32 is detachably supported a drum 35. To each drum 35 in the construction shown are bolted 100 two flanges 36, to which are hinged aprons 37 38, respectively, the free end of each apron being normally lifted slightly from the periphery of the drum by a spring 39. Mounted on the face of the apron 37 is a shear-blade 105 4, shown as a rectangular steel bar having its ends 41 furcated, as shown. (See Figs. 2 and 4.) These shear-blades may be stiffened and supported by a fillet 42, as shown. On the other drum 38 (see Fig. 5) two diagonally-placed bilaterally symmetrical shear-bars 5 are shown, each comprising an approximately 110

symmetrical semicircular central portion 51, straight portions 52, and arc-shaped portions 53. From the center of the portions 51 extends a shear-bar 54, located at approximately a right angle with an imaginary diagonal line on the apron relatively to which the shear-bars are mounted.

Just above the bed 11 of the machine and below the sprocket-wheel 2 are mounted two parallel longitudinally-extensible shafts, each consisting of parts 6 and 61, splined together. At the free end of each shaft portion 6 and 61 is a gear-wheel 62, connected by a suitable train (clearly shown in Fig. 2) to the main shaft 22. On each of the shaft portions 6 and 61 are secured rolls 63, four in all, which may have rubber facings 64. On one of the shafts 6 61 outside of the roll 63 are mounted stationary collars 65, one of which is shown in Fig. 7 and each of which supports a shear-blade 66. On the other shaft 6 61 is a pair of rolls 67, mounted to rotate with the shaft, and each having an apron 68 pivotally secured to and spring-supported from the roll, as are the aprons 37 and 38, before described. (See Fig. 7.) As is clearly shown in Figs. 1 and 2, the coöperating rolls 65 and 67 are located between the lower end of the uprights 13 and 14, the lower part of the uprights being cut away for this purpose.

Loosely and detachably mounted between the uprights 13 and 14 is a frame 7, shown as formed of parallel side bars 71 and cross-braces 72, the bars 71 having inwardly-curved upper ends 73 and reentrant curved portions 74, each corresponding to and freely fitting an arc of the sprocket-wheel 2, so that the projections 26 of the sprocket-chains fit around the sides of the bars 71, which are shaped to enter the recess 28 for a substantial part of their length. (See Figs. 3 and 6.) On each side of the frame 7 and extending from side to side thereof are bolted angularly-disposed shear blades or bars 75, the edges of which are at least flush with the edges of the bars 71. (See Fig. 6.)

The operation of the machine is as follows: The frame 7 is introduced into one end of a continuously-woven tubular web 8 and the frame slid down into the position shown in the drawings, Figs. 1 and 3, the upright 17 being first moved outward to the right of Figs. 1 and 3 for this purpose. When the upright 17 is again moved inward, so as to hold the frame 7 loosely in place, and the power applied to the machine, the web will be fed downward over the frame 7 by the engagement of the teeth 210 of the links 26 in the web. The rotation of the drums 35, one of which is located on each side of the frame 7, will bring the shear-blades 4 and 5 alternately over the shear-blades 75 on the frame and cut the web into shirt-bodies, as shown in Fig. 10. It will be seen that the bars 4 will cut the lower end of the shirt on both

sides of the web, the curved furcated ends 41 acting to remove a quadrantal gore from each side of the shirt, thereby producing skirts at the front and rear of the shirt. The next semirotation of the drums 35 brings the blades 5 against the blades 75 on the front and rear faces of the web—*i. e.*, on both sides of the frame 7. The semi-annular or arc-shaped portions 51 act to hollow out the neck of the two shirts, the parts 52 slope the shoulders, and the parts 53 cut the arm-scyes. In addition, the aprons 38 on one side of the frame 7 may have blades 54 to cut vertical slits at the back of the shirt. (See Fig. 5.) By cutting the shirts neck to neck and skirt to skirt, as shown in Fig. 10, a minimum waste of material is made. It is of course understood that the angularity of the shear-blades 4, 5, and 75 is so related to the feed speed of the web as to cut the shirt square of the material—*e. g.*, the blades 4 cut straight across the web.

The operation thus far described is, however, incomplete, as the edges of the web which pass over the outer faces of the bars 71 have not been severed. These edges are cut by the shear-blades 66 acting against the blades 69 on apron 68, the web being flattened and further fed downward by the pairs of rolls 63. The completely-severed bodies then drop through the bed 11 in a suitable receptacle. (Not shown.)

It is obvious that to cut the shirts with longer or shorter bodies it is only necessary to alter the speed-gear train between the worms 34 and the driving-shaft 22 so as to rotate the drums 35 at the desired speed. It is also clear that by delicately adjusting the upright 17 the side play of the frame 7 between the faces 29 of the links 24 may be adjusted to allow for different thicknesses of fabric. In the same way the machine is adjustable to cut shirt-bodies of different chest measurements from webs of different diameters by substituting frames 7 and aprons 37 and 38 of suitable widths, the shafts 6 61 being made telescopic or longitudinally self-adjusting and the collar 212 being made to slide on the shaft 211 for this purpose.

Reference to the dotted lines, Fig. 10, will show that the shear-blades in the other apron 38 (not shown in Fig. 5) are somewhat differently disposed—*i. e.*, to cut the front of the shirts including the neck-opening, shoulder-slope, and arm-scyes. It will be seen that the neck-opening cut by the portions 51 is of greater depth than that shown in Fig. 5 and that the slot cut by the blade 54 is omitted.

While I have described the construction and arrangement of the machine as adapted to cut a particular garment, it will be plain that changes easily within the skill of the mechanic can be made to adapt the machine to cut other garments or articles of any sort, whether the ends of these articles be of

straight or curved form and whether the articles are all of the same pattern, or of alternately different patterns, or on one or both sides. By the term "curved" as applied to 5 the shear-blades I of course include any deviation from a straight line. So by the term "frame," as used to describe the part 7, I intend to include any suitable device or means for entering the web and separating and supporting it. I wish it further understood that 10 many mechanical changes in the form and arrangement of parts and generally in the construction of the machine may be made without departing from my invention.

15 Where it is desired to use the particular machine illustrated for treating the web in other ways than by cutting it into desired articles, it would of course be possible to remove the rolls 35 and 67, as already described. This would of course eliminate the 20 cutting operations. By proportioning the width of the frame 7 to the diameter of the tubular web the latter may be stretched to any desired extent. By disconnecting the 25 pinions in the speed-gear train between the worms 34 and the main shaft 22 the positive action of the teeth 210 on the web would be eliminated and the web drawn over the frame only by means of the rollers 63, or, conversely, 30 by disconnecting the shaft by which the rollers 63 are driven from the main shaft the chains 24 could be used as the sole means of drawing the tubular fabric over the frame 7 or other supporting means.

35 Having thus described my invention, what I claim, and desire to secure by Letters Patent, is—

1. In a machine for treating fabric, means independent of the frame of the machine for 40 separating and interiorly supporting a tubular web, and means for maintaining said supporting means in operative position, said maintaining means being constructed and fitted to engage said supporting means solely 45 through the web.

2. In a machine for treating fabrics, means for longitudinally moving a tubular web, means located entirely within said web for separating and interiorly supporting it, and 50 means engaging said supporting means solely through the web for maintaining said supporting means in operative position.

3. In a machine for treating fabric, means independent of the frame of the machine for 55 interiorly supporting a tubular web, and means for engaging said supporting means solely through the web and thereby maintaining said supporting means in operative position and for moving the web over said 60 supporting means.

4. In a machine for treating fabric, means independent of the frame of the machine for 65 interiorly supporting a tubular web, means for engaging said supporting means solely through the web and thereby maintaining

said supporting means in operative position, and means for moving the web over said supporting means.

5. In a machine for treating fabric, a frame independent of the frame of the machine for 70 separating and supporting a tubular web, said frame having a shoulder, and means engaging said frame-shoulder through the web and for moving the web over said frame, said shoulder-engaging means forming the sole 75 support for said frame.

6. In a machine for treating fabric, a frame independent of the frame of the machine for 80 separating and supporting a tubular web, said frame having a shoulder, means for engaging said frame-shoulder solely through the web, and means for moving the web over said frame, said shoulder-engaging means forming the sole support for said frame.

7. A web-cutting machine comprising 85 means independent of the frame of the machine for interiorly supporting a tubular web, means for engaging said supporting means solely through the web, means for moving the web longitudinally, and means for cutting the web. 90

8. A web-cutting machine comprising means independent of the frame of the machine for interiorly supporting a tubular web, means for engaging said supporting means 95 solely through the web, means for continuously moving the web longitudinally, and means for cutting the web while in motion.

9. A web-cutting machine comprising means independent of the frame of the machine for interiorly supporting a tubular web, means for engaging said supporting means solely through the web, means for moving the web longitudinally, and means for cutting the web into tubular pieces, the ends of 105 which are of curved contour.

10. A web-cutting machine comprising means independent of the frame of the machine for interiorly supporting a tubular web, means for engaging said supporting means 110 solely through the web, means for moving the web longitudinally, and means for cutting the web into tubular pieces, the respective ends of each of which are of different contours. 115

11. A web-cutting machine comprising means independent of the frame of the machine for separating and supporting a tubular web, means for engaging said supporting means solely through the web, means for moving the web longitudinally, and means for cutting the web into tubular pieces, the contour of which differs on opposite sides of said 120 supporting means.

12. A web-cutting machine comprising 125 means independent of the frame of the machine for separating and supporting a tubular web, means for receiving the web and said supporting means, for engaging said supporting means through the web to maintain said 130

supporting means in position and for moving the web longitudinally, and means for cutting the web.

13. A web-cutting machine comprising means independent of the frame of the machine for separating and supporting a tubular web, means for moving the web longitudinally, and means for cutting the web, said cutting means being located in part on said supporting means, and in part exterior of the planes in which the web is guided.

14. In a machine for treating fabrics, a web separating and supporting frame, and means adapted to engage with said frame solely through the web supported thereon for maintaining said frame in operative position and for moving the web longitudinally over said frame.

15. In a web-cutting machine, means independent of the frame of the machine for interiorly supporting a tubular web, means for engaging said supporting means solely through the web, means for moving the web longitudinally over said supporting means, and means for cutting the web, a cooperating part of which cutting means is located on said supporting means.

16. In a web-cutting machine, means independent of the frame of the machine for interiorly supporting a tubular web, means for moving the web longitudinally over said supporting means, means for cutting the web comprising a part located on said supporting means and a second co-operating part located exterior of the plane of travel of the web, and means for moving one of said parts toward the other.

17. In a web-cutting machine, means independent of the frame of the machine for interiorly supporting a tubular web, means for moving the web longitudinally over said supporting means, and means for cutting the web comprising a relatively stationary part located on said supporting means and a movable part located exterior of the plane of travel of the web.

18. In a web-cutting machine, a web separating and supporting frame, a shear-blade on said frame, means for moving the web longitudinally over said frame, an outer shear-blade, and means for intermittently moving one of said shear-blades toward the other to cut the web.

19. In a web-cutting machine, a web separating and supporting frame, a shear-blade on said frame, means for moving the web longitudinally over said frame, an outer shear-blade, and means for intermittently moving said last-named shear-blade toward the shear-blade on said frame to cut the web.

20. In a web-cutting machine, a web separating and supporting frame, a shear-blade on said frame, means for moving the web longitudinally over said frame, an outer

shear-blade, and means for intermittently moving one of said shear-blades toward the other to cut the web, one of said shear-blades being of curved contour.

21. In a web-cutting machine, a web separating and supporting frame, a shear-blade on said frame, means for moving the web longitudinally over said frame, an outer shear-blade of curved contour, and means for intermittently moving one of said shear-blades toward the other to cut the web. 75

22. In a web-cutting machine, a web separating and supporting frame, a shear-blade on said frame, means for moving the web longitudinally over said frame, a plurality of outer shear-blades of different contours, and means for alternately moving said outer shear-blade relatively toward the shear-blade on said frame to cut the web. 80

23. In a web-cutting machine, a detachable web separating and supporting frame, means for moving the web longitudinally over said frame, and means adapted to engage with said frame solely through the web supported thereon for maintaining said frame in operative position, said supporting means being adjustably mounted to engage with frames differing in dimensions from each other. 85

24. In a web-cutting machine, a web separating and supporting frame, a shear-blade on said frame, means for moving the web longitudinally over said frame, an outer shear-blade, means for intermittently moving one of said shear-blades toward the other to partially sever pieces of the web, and additional means for completing the cutting off of such pieces from the web. 95

25. In a web-cutting machine, a web separating and supporting frame, means for supporting said frame within a tubular web, means for moving the web over said frame, means for partially severing pieces of the web during its movement over said frame, and means for completing the cutting off of such pieces after they have moved past said frame. 105

26. In a web-cutting machine, a web separating and supporting frame having edge portions and approximately parallel sides, means for supporting said frame within a tubular web, means for moving the web over said frame, means for severing the portions of the web adjacent the parallel sides of said frame during its passage thereover, and additional means for severing the edge portions of the web after it has moved past said frame. 115

In testimony whereof I have signed this specification in the presence of two subscribing witnesses.

ARTHUR JAMES CUMNOCK.
